W. BUTLER

MOP WRINGER

Filed March 24, 1926

Inventor:
William Butler,
By Jas. C. Noblesmith
Attorney.

UNITED STATES PATENT OFFICE.

WILLIAM BUTLER, OF PHILADELPHIA, PENNSYLVANIA.

MOP WRINGER.

Application filed March 24, 1926. Serial No. 96,948.

My invention relates to mop wringers, and it has particular relation to a device adapted to be mounted in a bucket or pail for the purpose of gripping the lower end 5 of a mop whereby the excess water may be wrung therefrom by manually twisting the mop while the lower end is thus held.

The principal object of my invention is to provide a device of the character aforesaid which will be efficient in operation, which may be inexpensively constructed, and which is adapted to be mounted in a bucket or pail of ordinary construction for the purpose of gripping a portion of the mop while 15 the excess water is being wrung therefrom by manually twisting the mop.

The nature and characteristic features of my invention will be more readily understood from the following description, taken 20 in connection with the accompanying drawings forming part hereof, in which:

Figure 1 is a top or plan view of a mop wringer embodying the main features of my present invention, the same being shown 25 mounted in a bucket or pail of ordinary construction, and the mop wringer being shown in the open position;

Fig. 2 is a similar view, but with the mop wringer shown in the closed or gripping 30 position, the mop, however, being omitted for the purpose of clearness;

Fig. 3 is a vertical central section, taken approximately on the line 3—3 of Fig. 2, the lower end of the mop being shown in 35 position and gripped by the wringer;

Fig. 4 is an enlarged detail view illustrating the construction of the bracket for securing the wringer in place in the bucket; and

Fig. 5 is a side elevation of one of the 40 foot members provided for holding the bucket in a fixed position on the floor while the wringing operation is taking place.

Referring to the drawings, in the particular embodiment of my invention therein shown, 10 is a bucket or pail of ordinary construction, preferably of the type in common use, made of sheet metal such as galvanized steel. Secured to the side wall of 45 the bucket, near the bead 11 usually provided at the top portion thereof, are inner and outer sector plates 12 and 13 respectively. These sector plates are secured to the bucket and to each other by means of 50 bolts 14, which pass through said plates and through the wall of the bucket,

60 Mounted in the sector plates 12 and 13 is a bracket member 15, the outer end of which is threaded, as at 16, for the purpose of mounting thereon nuts 17 and 18, which serve to secure the bracket member 15 to the sector plates 12 and 13, as well as to the wall of the bucket 10, which extends between said plates.

65 The inner end of the bracket member 15 has an enlarged portion 19, in which there is secured an arm 20. The portion of the arm 20 which is mounted in the enlarged portion 19 of the bracket member 15 is curved as at 21. Said arm extends from said curved portion 21 in a straight portion 22, and the outer end thereof passes through the wall of the bucket 10, as at 23. In this manner the arm 20 will be fixedly positioned with respect to the bucket 10.

70 The end of the curved portion 21 of the arm 20 has pivotally connected thereto, as at 24, a curved link 25. The other end of the curved link 25 is pivotally connected, as at 26, to one end of an arm 27. The end 75 of the arm which is pivotally connected to the link 25 is preferably of substantially the same curvature, as at 28, as that of the curved end 21 of the arm 20. The intermediate portion of the arm 27 has a curvature, as at 29, of greater radius than the portion at 28. The arm 27 thence extends in a straight portion 30, and terminates in an outwardly extending portion 31.

80 Mounted in the shank portion of the bracket member 15 is an auxiliary bracket 32, which preferably extends downward, thence horizontally as at 33, and thence upwardly as at 34. The upward extension 34 of the auxiliary bracket 32 is provided with 85 a plate member 35, in which are mounted a plurality of upwardly extending rods or wires 36, which extend within and in proximity to the curved portion 21 of the arm 20. The rods or wires 36 are more or less 90 flexible, for a purpose which will be presently understood.

95 There are also provided devices for holding the bucket to the floor, comprising members 37, preferably made of flat metal and having bent over portions 38 which are 100 adapted to extend down on the inside of the bucket, passing over the beaded portion 11 thereof. The main portion of the member 37 extends downward on the outside of 105 the bucket, and is provided at the bottom with an outwardly extending foot portion 39.

which is adapted to be engaged by the foot of the user. There are preferably provided two of such devices, mounted on opposite sides of the bucket, whereby the user may place one foot on each of the extensions 39 thus provided, and thereby firmly hold the bucket 10 against movement on the floor when the strain is put on the structure during the wringing operation.

10. The operation of the device may now be explained. The bucket has the device above described mounted therein, and contains a suitable quantity of water for washing purposes. The mop, which may be of any preferred construction, is first manipulated in the water whereby the same will be cleansed of any impurities, but at the same time will take up a considerable quantity of water. As is well known, it is usually desired, before 20 again using the mop, to remove the excess water therefrom.

In the use of the device of the present invention, the lower end of the mop is positioned within the curved portion 21 of the 25 stationary arm 20, the same being engaged by the rods or wires 36. The arm 27, and consequently the curved link 25, are now brought around until the curved portion 28 of the arm 27, and the curved link 25 engage 30 the lower end of the mop, and in conjunction with the curved portion 21 of the arm 20, serve to grip the same as the mop is twisted by the user to wring the excess water therefrom.

35. The wires or rods 36 are preferably of sufficient flexibility as not to interfere with the twisting of the mop, while at the same time they will serve to assist in gripping the same to remove more effectively the excess water 40 from the lower portion of the mop, which extends below the gripping portion of the arms 20 and 27 and the link 25.

It should, however, be understood that the provision of the wires or rods 36 is not absolutely essential, as the same may, in some 45 instances, be omitted if desired, without departing from the spirit of my invention.

It should be noted, however, that the pivotal connections at 24 and 26, whereby the 50 ends of the curved link 25 are connected to the respective ends of the arms 20 and 27, are preferably made quite loose, so that the arm 27 may be readily swung over the top of the bucket, and be permitted to clear the 55 ears 40 by means of which the bail handle 41 is secured to the bucket.

The floor members 37, for holding the bucket against movement on the floor during the wringing operation, may be readily 60 positioned at any desired place to suit the convenience of the user. It will also be found in practice that the outward curvature, as at 31, of the end of the arm 27, may be engaged by the leg of the user and the 65 same thereby pushed to add to the efficiency

of the gripping action of the curved portions of the arms 20 and 27 and the link 25, which engage the lower end of the mop.

It will be seen that there is thus provided a relatively simple, yet effective form of mop wringer, which may be readily mounted in a bucket of ordinary construction, which device may be inexpensively constructed and easily and quickly mounted in place in the bucket, without any great skill being required in so mounting the same, thus greatly facilitating the shipping of the device in "knock-down" form.

Having thus described the nature and characteristic features of my invention, what I claim as new and desire to secure by Letters Patent, is:

1. A mop wringer adapted to be mounted in a bucket, comprising a stationary arm having a curved portion, a movable arm having a similar curved portion, and a link having its ends in free pivotal connection with the ends of said curved portions of said arms, the arrangement being such that the lower end of the mop may be gripped by the curved portions of the arms and the connecting link when the movable arm is in the clamping position.

2. A mop wringer adapted to be mounted in a bucket, comprising a stationary arm having a curved portion, a movable arm having a similar curved portion, and a curved link having its ends in free pivotal connection with the ends of said curved portions of said arms, the arrangement being such that the lower end of the mop may be gripped by the curved portions of the arms and the connecting link when the movable arm is in the clamping position.

3. A mop wringer adapted to be mounted in a bucket, comprising a stationary arm having a curved portion, a movable arm having a similar curved portion, a curved link having its ends in free pivotal connection with the ends of said curved portions of said arms, a bracket member in which the curved portion of the stationary arm is mounted, and means for securing said bracket member to the side wall of the bucket, the arrangement being such that the lower end of the mop may be gripped by the curved portions of the arms and the connecting link when the movable arm is in the clamping position.

4. A mop wringer adapted to be mounted in a bucket, comprising a stationary arm having a curved portion, a movable arm having a similar curved portion, a curved link having its ends in free pivotal connection with the ends of said curved portions of said arms, a bracket member in which the curved portion of the stationary arm is mounted, sector plates in which the bracket member is secured, and means for securing said sector plates to the side wall of the

bucket, the arrangement being such that the lower end of the mop may be gripped by the curved portions of the arms and the connecting link when the movable arm is in the 5 clamping position.

5. A mop wringer adapted to be mounted in a bucket, comprising a stationary arm having a curved portion, a movable arm having a similar curved portion, said movable arm having a free swinging connection with said stationary arm, and a plurality of flexible wires positioned to extend into the space enclosed by the curved portions of the arms, the arrangement being such that the 10 lower end of the mop may be gripped by the curved portions of the arms when the movable arm is in the clamping position and engaged by the flexible wires when so gripped.

15 6. A mop wringer adapted to be mounted in a bucket, comprising a stationary arm having a curved portion, a movable arm having a similar curved portion, a curved link having its ends in free pivotal connection with the ends of said curved portions of said arms, and a plurality of flexible wires positioned to extend into the space enclosed by the curved portions of the arms, the arrangement being such that the lower end of 20 the mop may be gripped by the curved portions of the arms and the connecting link when the movable arm is in the clamping position and engaged by the flexible wires when so gripped.

25 7. A mop wringer adapted to be mounted in a bucket, comprising a stationary arm having a curved portion, a movable arm having a similar curved portion, a curved link having its ends in free pivotal connection with the ends of said curved portions of said arms, a bracket member in which the stationary arm is mounted, means for securing said bracket member to the side wall of the bucket, an auxiliary bracket carried by the 30 aforesaid bracket member, and a plurality of flexible wires supported by the auxiliary

bracket and extending into the space enclosed by the curved portions of the arms, the arrangement being such that the lower end of the mop may be gripped by the 50 curved portions of the arms and the connecting link when the movable arm is in the clamping position and engaged by the flexible wires when so gripped.

55 8. A mop wringer adapted to be mounted in a bucket, comprising a stationary arm having a curved portion, a movable arm having a similar curved portion, a curved link having its ends in free pivotal connection with the ends of said curved portions of said arms, a bracket member in which the stationary arm is mounted, sector plates in which the bracket member is secured, means for securing said sector plates to the side wall of the bucket, an auxiliary bracket carried by the aforesaid bracket member, and a plurality of flexible wires supported by the auxiliary bracket and extending into the space enclosed by the curved portions of the arms, the arrangement being such that the 60 lower end of the mop may be gripped by the curved portions of the arms and the connecting link when the movable arm is in the clamping position and engaged by the flexible wires when so gripped.

65 9. A mop wringer adapted to be mounted in a bucket, comprising a stationary arm having a curved portion, a movable arm having a similar curved portion, and a link having its ends in free pivotal connection with the ends of said curved portions of said arms, the arrangement being such that the lower end of the mop may be gripped by the curved portions of the arms and the connecting link when the movable arm is in the 70 clamping position and engaged by the flexible wires when so gripped.

75 In testimony whereof, I have hereunto signed my name.

WILLIAM BUTLER.
